BLADE FOR A SNOW SHOVEL

Orville D. Hoxie and John MacDonald, Grand Rapids, Mich., assignors to Bissell Inc., Grand Rapids, Mich., a corporation of Michigan

Filed Aug. 8, 1966, Ser. No. 3,391

Term of patent 14 years

Int. Cl. D8—01

U.S. Cl. D39—1

FIG. 1.

FIG. 2.

FIGURE 1 is a perspective view of a snow shovel blade showing our new design; and

FIG. 2 is a front elevation thereof, the side opposite being a mirror image with the concave front elevation portions being convex.

The characteristic features of our design reside in the specific configuration and arrangement of the stiffening rib elements on the snow shovel blade shown herein.

We claim:

The ornamental design for a blade for a snow shovel, substantially as shown and described.
